Application July 22, 1939, Serial No. 285,972

6 Claims. (Cl. 119—37)

This invention relates to egg incubators, that is containers such as incubators in which eggs may be hatched. It relates more particularly to certain improvements in methods of and apparatus for obtaining and maintaining the desired air temperature, humidity and circulating conditions within such an incubator.

In the large, present day incubators it has previously been proposed to construct the incubator in the form of a large room or chamber having a central corridor extending lengthwise of the chamber, a door at one end of the corridor to provide access into the incubator, columns of egg trays disposed on either side of the central corridor and supported in such a manner that they may be tilted at intervals during incubation, horizontal hatching racks disposed on either side of the corridor below the tilting trays, and curtains extending lengthwise of the corridor on either side thereof for shutting off the corridor from the tilting trays in order to facilitate the proper air circulation and atmospheric control. In previous incubators provision has been made for controlling the temperature and humidity of the air by various means and the present invention relates broadly to improvements in air conditioning and controlling of incubators or other relatively large chambers or housings of the general type above described.

It is, of course, understood that during the incubation of eggs the temperature and humidity conditions must be maintained within very close limits and must be varied at certain times during the incubation period. At some stages during the operation of the incubator it is necessary to add heat from an external source, while at other times, due to the heat given off by the eggs, it is necessary to cool the air circulating through the incubator in order to prevent the temperature from going too high. Furthermore, during all stages of incubation, except the hatching period, the humidity should be maintained at a certain predetermined value while during hatching the humidity should be raised to a higher value.

It is among the objects of our invention to provide an improved method of and apparatus for controlling the air conditions within a housing, such as an incubator or the like, which is simple, economical to operate, and provides a very flexible and effective temperature and humidity control while maintaining an even circulation of air of the same temperature and humidity throughout all parts of the incubator. Other objects of our invention include: the provision of means for

conditioning a certain predetermined proportion of the air circulating in the incubator and returning the conditioned air to the circulating system; the provision of an air conditioning system for incubators or the like which is compact, simple in construction and arrangement of its elements, and adapted to heat or cool, or increase or decrease the relative humidity of air passing therethrough; the provision of a method and apparatus for maintaining proper temperature conditions throughout an incubator regardless of variations in humidity within the incubator; and the provision of an air conditioning unit which, in addition to its other functions, is adapted to remove entrained down, etc. from the air passing therethrough.

The above and other objects of our invention will appear from the following description of a preferred embodiment thereof, reference being had to the accompanying drawings, in which—

Figure 1 is a vertical longitudinal cross-sectional view through an incubator embodying our improvements, the section being taken substantially on line 1—1 of Figure 2.

Figure 2 is a vertical transverse cross-sectional view of the same incubator, taken substantially on line 2—2 of Figure 1.

Figure 3 is a more or less diagrammatic horizontal cross-sectional view taken on line 3—3 of Figure 1 and illustrating the air circulating fans, manifolds, ducts, etc.

Figure 4 is a diagrammatic layout of the electrical connections between the thermostat which is responsive to the wet bulb temperatures and the motor which drives the fan and controls the flow of air through the humidifying conduit.

Fig. 5 is a diagrammatic view showing means for controlling the heating coils.

The incubator housing 10 is provided with heavy insulated walls and is generally of elongated, rectangular shape. A door 11 is located at one end of the incubator and opens into the central corridor 12 which extends the entire length

45 of the housing 10. Above the corridor 12 and extending the length of the housing 10 is a pair of beams 14 and 15, suitably secured to the end walls of the housing 10. Tiers of tiltable egg trays 16 are suspended from the side walls of the housing 10 and the beams 14 and 15 by means of vertical bars 13 which are adapted to be shifted vertically to tilt the trays in well known manner. These trays 16 are disposed in columns along both sides of the central corridor 12, and air spaces 17 (see Fig. 2) are provided above each bank of trays.

Horizontally arranged hatching racks 18 are located below each bank of trays 16 and the removable down-catching screens 19 extend from the corridor 12 between the hatching racks 18 and the tilting trays 16. Slidable curtains 20, of cloth or other suitable material, normally cover the sides of the corridor 12 and extend from a point adjacent the top layer of trays 16 down substantially to the down-catching screens 19. During loading of the trays and removing of the chicks these curtains can be slid back out of the way, as indicated in Figure 1.

The ceiling of the corridor 12 comprises a fan panel 22 which extends across the top of the corridor and is secured to the beams 14 and 15. This panel is provided with spaced, screened, fan openings 23 above which are mounted the electrically driven fans 24a, 24b, 24c, and 24d (see Fig. 3). In order to assist in obtaining the proper circulation, the blades of these fans are located as closely as possible to the screens covering the fan openings 23.

The fan panel 22 also separates the corridor 12 from the top of the housing 10 forming an air space which is referred to at 27 on Figure 1 of the drawings. This air space 27 is connected to each of the side spaces or chambers 17 through the somewhat restricted, elongated passages 25 and 26, which are defined by the roof of the housing 10 and the beams 14 and 15.

An air conditioning cabinet, generally indicated at 30, is located at the end of the corridor 12 opposite the door 11. This cabinet is disposed largely outside of the housing 10, as shown in Figure 1, and access thereto may be had from the corridor 12 through a removable door or panel 31. Air from the corridor 12 may enter the cabinet 30 through louvres 32 (which may be closed when the apparatus is used for storage purposes) disposed in an opening located just below the door or panel 31 and extending across the width of the cabinet 30. Part of the air that enters through the louvres 32 passes through a pipe elbow 32a which directs it upwardly through the cabinet toward the top outlet opening 33 which is disposed in the uppermost portion of the air conditioning cabinet 30 and directs air into a manifold 53 located in the housing 10 above the fan panel 22.

The side walls of the cabinet 30, which protrude outside of the housing 10, are covered to a large extent by the exhaust ducts 35 (see Figs. 2 and 3) which extend from the bottom of the louvres 32 to a point slightly below the outlet 33. Outlet ports 39 are provided at the top of each of the exhaust ducts 35. The rear wall of the cabinet 30 is covered to a considerable extent by the air inlet duct 36 which extends from approximately the level of the bottom of the louvres 32 to the top of the outlet ducts 35. The upper portion of the cabinet 30, which is not protected by the inlet and outlet ducts, is covered by suitable insulating material 37.

Air which is to be removed from the system passes out through the exhaust ports 38 in the sides of the cabinet 30 and the ducts 35 and is discharged into the atmosphere through the outlet ports 39. Fresh outside air may enter the bottom opening 40 in the inlet duct 36 and is admitted to the cabinet 30 through the inlet port 41 which is provided with an adjustable damper 42 to control the amount of fresh air admitted to the incubator.

The cabinet 30 houses the various air condi-

tioning elements. These include the electrical heating coils 43, a water cooling coil 44, a warm water spray nozzle 45 and the cold water spray jets 46. All of these air conditioning elements are connected to suitable sources of water or electrical current (not shown). The cold water sprays 46 are disposed just above the cooling coil 44 while the warm water humidifier spray 45 is disposed below the cooling coil 44 in the outlet 10 of the elbow 32a.

In the preferred embodiment of our invention, which is illustrated in the drawings, the warm water spray jet 45 and the cold water spray jets 46 are each connected to a common source of supply of cold water. Spray jets 46 are supplied directly through the valve 47 but the water discharged through the jet 45 passes through a valve 48 and a pre-heating coil 49 located in the upper portion of the cabinet 30. Thus, the jet 45 is supplied with water which has been heated to a certain extent by the air which passes around the coil 49. Any excess of water which may collect in the bottom of the air conditioning cabinet is conducted by pipes 30a and 30b, which extend from the elbow 32a and the bottom of the chamber 30 respectively, to the drain 50.

The air outlet 33 from the cabinet 30, as noted above, opens into a transverse manifold 53, located above the end portion of the fan panel 22.

30 Air distributing ducts 54 and 55 extend from the opposite ends of the manifold 53 (see Fig. 3). These ducts are provided with openings 60a, 60b, 60c, and 60d in duct 54 and 61a, 61b, 61c and 61d in duct 55, which are located adjacent the fans 24a, 24b, 24c and 24d. The ducts 54 and 55 are supported by the beams 14 and extend parallel thereto, and, as illustrated, are of rectangular cross-section. The air outlet openings in the ducts 54 and 55 are so proportioned in size that a substantially equal amount of heat units will be supplied to or removed from the air passing through each of the fans 24a, 24b, 24c and 24d. If desired adjustable slides or dampers may be provided or the openings may merely be cut to the proper size. In the drawings no dampers are shown but they form a modification within the knowledge of those skilled in the art.

As may be seen in Figure 2, the normal flow of air in the incubator is from the fans 24a, 24b, 24c and 24d, downwardly to the floor of the corridor 12 and then laterally into the side sections and upwardly through the racks 18 and the trays 16 to the chambers 17. From the chambers 17 the air passes through the openings 25 and 26 into the space 27 where it is again picked up by the fans and recirculated through the incubator. Due to the resistance of the tiers of the trays 16 and the restricted passages 25 and 26, the air in the incubator, particularly in the lower portion of the corridor 12 and in the egg trays, is normally at a higher pressure than the air in the central chamber 27. In the absence of any means to prevent such an occurrence, the continuous circulation of the air by the fans 24a, 24b, 24c and 24d may tend to cause a stratification and the temperature of the air at one cross-sectional portion of the incubator may be different from that at another due to differences in the amount of heat and/or moisture absorbed by or given off from the eggs. The resulting hot spots or cold spots are distinctly disadvantageous to successful incubator operation.

As noted above, the pressure in the corridor 12 is higher than that in the chamber 27, and by

providing the large opening through the louvres 32, a natural flow of air occurs through the cabinet 30 entering the louvres and passing out through the outlet 33 into the distributing ducts. This natural flow of air causes a recirculation and redistribution of air longitudinally in the machine which distributes the moisture and controls the temperature from one end of the housing to the other, keeping it uniform throughout. It will be noted that the louvres 32 are materially larger than the opening of the elbow 32a. A fan 62, which is preferably driven by an electric motor, is disposed in the elbow 32a adjacent the louvres 32. This fan is of the type having overlapping blades which, when the fan is stopped, causes a material restriction to the flow of air through the elbow passage. When the fan is stopped there will still be a circulation through the cabinet 30 as air will enter the louvres 32 around the elbow 32a and fan 62. This air, going around the elbow, is used to level off the temperature and recirculate air through the cabinet 30, thus adding or subtracting heat from the housing 10 as needed.

The second function of the cabinet 30 is to control the humidity of the air in the housing 10. The spray nozzle 45 operates continuously and discharges a mist or spray of water into the outlet end of the elbow 32a at all times. This spray is substantially at the wet bulb temperature of the air in the housing 10 because it passes through the coil 49 located in the path of air leaving the cabinet 30. If the fan 62 is stopped there will be only a relatively slow movement of air through the elbow 32a and not enough air will move through the elbow to evaporate all of the fog or mist produced by the nozzle 45. Under these conditions there will be created a deficiency in moisture within the incubator itself due to the addition of fresh air through the duct 36 and the fact that not enough moisture is added to the air circulated through the cabinet 30 to maintain the humidity. When the humidity within the housing 10 becomes too low the mist or spray in the elbow 32a evaporates rapidly, which cools and saturates the air near thermostat 63 and causes the thermostat 63 to start the fan motor 62 and draw air into elbow 32a. These connections are diagrammatically illustrated in Figure 4 and include a needle or finger *a* which is moved by a spiral thermostatic element 63. The needle *a* is connected to one side *b* of the line current and the contact *c* is adapted to engage another contact *d* when the wet bulb temperature indicated by the thermostat 63 falls to a predetermined value due to a reduction in the humidity of air from the housing 10. Making this contact completes the circuit through the relay coil *e* to the side *f* of the supply line and energization of the relay coil *e* closes the normally open switch *g* completing the circuit to the motor of the fan 62, as is clearly seen in Figure 4. It will be understood that the relay coil and switch *e* and *g* are diagrammatically illustrated and that they may assume any form found suitable and desirable. Such relays are well known in the art and form no part of the present invention. As the fan starts a draft of air flows through the elbow 32a, creating a fast current of air past the spray nozzle 45 which evaporates the mist from the nozzle and passes on into the housing 10 through the outlet 33 and the distributing ducts. When the fan is operating moisture is added to the housing 10 at a greater rate than when the fan is not

operating. This added moist air causes the humidity and wet bulb temperature within the incubator 10 to increase and thus air which is being drawn into the elbow 32a will increase in humidity and wet bulb temperature accordingly. As the humidity increases in the housing 10 the evaporation in the elbow 32a decreases, the air near thermostat 63 becomes warmer and the thermostat 63 is actuated to cause the fan motor 62 to stop, the blades restrict but do not completely stop the passage of air through the elbow 32a, and the humidity is permitted to fall until it again becomes too low when the above described cycle is repeated.

15 Air will pass through the louvres 32 around the elbow 32a both when the fan is running and when it is stopped. However, when the fan is running, the volume of air passing through the louvres and the cabinet outside of the elbow will be relatively less than when the fan is shut off and in this way the humidity in the housing 10 may be raised and lowered in accordance with the automatic control established by the thermostat 63 and the spray 45.

The spray 45 is directed downwardly into the elbow 32a and countercurrent to the air passing through the elbow. This spray produces a mist or fog which evaporates into the air passing through the elbow and it has been determined that this air assumes the wet bulb temperature 25 in the same manner as though a thermometer were suspended in this air stream with a moist wicking surrounding the bulb. Therefore, the thermostatic element 63, which is suspended in the air stream at about the top of the elbow, is 30 at all times located in the air which is passing through the fog or mist and will assume the same temperature as a wet bulb hygrometer. This thermostat 63 is connected by suitable electrical connections (see Fig. 4) to start and stop the 35 fan 62. Thus, by means of the spray nozzle 45, the elbow 32a, the fan 62 and the thermostatic element 63, we have provided an automatic humidity control which, in one position of the 40 thermostat will tend to produce a deficiency of moisture in the housing 10 and in another position of the thermostat, i. e., the on position with the fan running, will tend to produce an excess of moisture in the housing 10.

50 From the above it will be observed that a certain proportion of the air circulated within the incubator may be withdrawn through the louvres 32, subjected to air conditioning in the cabinet 30, and reintroduced into the circulating air. Incident to the air conditioning, a certain proportion of the air may be permitted to escape through the outlet ducts 35 and a certain amount of new air may be admitted through the inlet duct 36. The withdrawing of the air for conditioning purposes and reintroduction of the conditioned air into the space 27 above the fans 24 causes turbulence and disturbance in the normal circulation of air in the incubator thus preventing stratification and insuring uniform temperature and humidity conditions throughout. The withdrawal of air through the louvres 32 and recirculation thereof through the duct system sets up a transverse movement of air through the cabinet creating a condition which breaks up the tendency toward stratification.

60 It will be understood that suitable temperature and humidity indicating instruments may be located where they can be observed by the operator. The heating coils 43 are conveniently automatically controlled from a thermostat located

within the housing 10. Any suitable thermostat may be used for this purpose including the thermometer controller made by the Bristol Company of Waterbury, Conn., and illustrated in Figs. 1 and 2 and somewhat diagrammatically in Fig. 5. There the spirally wound tube 100 which extends lengthwise of the incubator in one air space 17 communicates thru a capillary tube 101 with a spiral tube 102 which carries an indicator 103 which can complete an electrical circuit either by engaging contacts 104 or 105 thru a relay 107 which opens and closes a switch to connect a source of electricity (not shown) with leads 108 connected to heating coils 43. The indicator and tube 102 are positioned outside of the incubator in housing 106. Expansion or contraction of liquid in coil 100 causes movement of indicator 103 toward contacts 104 or 105. When the liquid contracts due to decrease in temperature of the air about tube 100, the indicator 103 moves to complete a circuit thru one of its contacts and thereby connects the heating coils 43 with a source of current. When the liquid in tube 100 expands the indicator 103 is shifted to engage with the other contact, thereby opening the circuit thru which current is supplied to coils 43. The spray nozzles 46 may be manually controlled to provide additional cooling when necessary. By proper regulation of the amount of new air which is admitted through the duct 36, along with the other temperature and humidity control elements, conditions within the entire incubator can be accurately and easily maintained at the proper values. By withdrawing and conditioning a certain percentage of the air circulated within the incubator and then re-distributing this conditioned air evenly throughout the entire incubator, a control efficiency is obtained which has not previously been possible.

In addition to the temperature and humidity conditioning functions of the cabinet 30, the water sprays 45 and 46 are available to remove entrained down from the circulating air and tend to eliminate carbon dioxide from the air by absorption thereof by the water sprays. Because the fresh air inlet duct 36 and the outlet ducts 35 are disposed on the outer walls of the cabinet 30 an effective heat exchange and insulating result is obtained.

In certain instances it has been found desirable to utilize the above described egg container for cold storage purposes during the off-season when eggs are not being hatched. Our present container or incubator is particularly well adapted to this use and we have provided a series of cooling coils 64 located in a compartment 65 disposed just below the cabinet 30. During the normal operation of the incubator this compartment 65 is closed off from the cabinet 30 by a removable panel 66. Another removable panel 67 is adapted to close an inlet opening 68 in front of the fan 69. Ordinarily, when the incubator is operating, the panels 66 and 67 are in position and the cooling apparatus of the compartment 65 is inoperative. However, when it is desired to cool the entire incubator to a degree not possible by means of the cooling equipment of the cabinet 30, the panels 66 and 67 are removed, the coil 64 connected to any suitable refrigeration machine (not shown) and a coolant circulated therethrough, and fan 69 started in operation. Air will thus be withdrawn from the bottom of the corridor 12, forced over the cooling pipes 64 and discharged upwardly through the cabinet 30.

The cooled air will be distributed through the header 53 and ducts 54 and 55. If desired the fans 24a, 24b, 24c and 24d, or part of them, may be operated to assist in the circulation of air through the structure. The louvres 32 are preferably closed during cold storage operation of the housing so that all of the air from the fan 69 will pass through the cabinet 30 to the upper distributing ducts 53, 54, 55, etc. By combining the auxiliary cooling equipment housed in the compartment 65 with the main air conditioning cabinet 30 and the distributing means for circulating air from the cabinet, a very efficient cooling system is obtained.

Although we have described the illustrated embodiment of our invention in considerable detail, it will be understood by those skilled in the art that numerous variations and modifications may be made in the procedure and apparatus outlined herein without departing from the spirit of our invention. We do not, therefore, wish to be limited to the particular procedures and devices shown herein but claim as our invention all forms thereof coming within the scope of the appended claims.

We claim:

1. An incubator comprising an elongated housing, tiers of egg trays disposed along each side of the interior of said housing and defining a central corridor, a plurality of aligned fans located above said central corridor to propel air downwardly in said corridor, a pair of ducts disposed along both sides of said aligned fans and having openings therein adjacent the inlet side of each of said fans and above said corridor, an air conditioning cabinet located at one end of said corridor and having an opening therein whereby air in said corridor may enter said air conditioning cabinet, said cabinet having an inlet for fresh air and an outlet for exhaust air, and a manifold leading from said air conditioning cabinet to said pair of ducts.

2. In an incubator, a housing, tiers of egg trays therein defining a corridor, a plurality of aligned air circulating means located above said corridor to propel air downwardly in said corridor, a pair of adjacent air distributing ducts located on opposite sides of and adjacent to said aligned air circulating means, an air conditioning cabinet, at one end of said corridor air conditioning means within said cabinet, and means whereby air may be withdrawn longitudinally from said corridor at one end thereof into said cabinet and then returned to said air distributing ducts, said ducts having outlet openings adjacent to said air circulating means to deliver conditioned air into circulating air descending into said corridor.

3. In apparatus of the type described, a housing, means for circulating air in said housing, means for withdrawing and conditioning a small portion of such circulating air including an air conducting conduit having an inlet and an outlet, said inlet being connected to receive air from said housing, a fan adjacent the inlet to said conduit, means for driving said fan, means for continuously spraying water in finely divided condition into said conduit, a thermostat supported in said spray, said thermostat being connected to control said fan driving means and being responsive to the temperature of the air in the conduit whereby an increase of said temperature above a predetermined value will stop said fan and a decrease of said temperature below a predetermined value will start said fan, means of

returning the withdrawn air to said housing, and means for maintaining the air being withdrawn from the housing at a substantially constant dry bulb temperature which is higher than the temperature of the air about said thermometer, said means for circulating air in said housing serving, when said fan is not in operation, to create a flow of air thru said air conducting conduit.

4. In an incubator, the combination of a housing, means for circulating air in the housing, means for withdrawing air from said housing in a direction transverse to the direction of circulation of air in the housing, means for continuously discharging a spray of water into said withdrawn air, a thermostat disposed in the zone of said spray and in the path of said withdrawn air, and means, responsive to said thermostat, for varying the quantity of air withdrawn from said housing whereby, when the relative humidity of the air in the housing falls below a predetermined value, the quantity of air withdrawn from the housing will be increased and such increase maintained until the relative humidity of the air in the housing is raised to a predetermined value whereupon the quantity of air withdrawn from the housing will again be reduced, means for maintaining the air being withdrawn from the

housing at a substantially constant dry bulb temperature, higher than the temperature of the air about the said thermostat, and means for returning the withdrawn air to the housing.

5. The method of circulating and conditioning air in an incubator having a central aisle and egg compartments on opposite sides thereof which includes the steps of circulating the majority of the air within the incubator in two closed loop paths which are substantially co-extensive in axial length with the interior length of the incubator, said circulating air moving down thru the aisle to its lower portion, then moving in opposite directions into the lower parts of said egg compartments, then up thru the latter and then toward each other and into the top of said aisle, withdrawing air from the lower part of said aisle at one end thereof, conditioning it, returning it to the interior of said paths, introducing it at a plurality of places along said aisle near its upper end into air moving downwardly in said aisle and thoroughly mixing it with circulating air in the aisle before such air enters the lower portions of said egg compartments.

CERTIFICATE OF CORRECTION.

Patent No. 2,319,091.

May 11, 1943.

SAMUEL HAROLD SMITH, ET AL.

It is hereby certified that error appears in the printed specification of the above numbered patent requiring correction as follows: Page 5, second column, line 4, claim 4, after the word and period "housing." insert the following as claim 5 -

5. The method of circulating air in an incubator having a central aisle and egg compartments on opposite sides thereof which includes the steps of circulating the majority of the air within the incubator in closed loops whose axes extend horizontally thruout substantially the entire interior length of the incubator, said loops extending downwardly in said aisle laterally and then upwardly thru said egg compartments and laterally to above the aisle, withdrawing small amounts of the air from one end of said aisle, conditioning it, returning it to the interior of said loops and mixing it at a plurality of places along said loops with the circulating air descending in said aisle. --;

and that the said Letters Patent should be read with this correction therein that the same may conform to the record of the case in the Patent Office.

Signed and sealed this 3rd day of October, A. D. 1944.
